WRINGER MOP

William E. Kautenberg, Freeport, Ill., assignor to W. E. Kautenberg Co., Freeport, Ill., a corporation of Illinois

Application November 15, 1954, Serial No. 33,107

Term of patent 14 years

(Cl. D9—2)

FIG. 1

Figure 2 is a perspective front view of the mop with the wringer plate disengaged and partly extended; and

Figure 3 is a perspective rear view of the mop with the wringer plate in wringing position and with the handle shown broken away in part to indicate indeterminate length.

The handle is broken away in Figs. 1 and 2 for the convenience of illustration only.

The characteristic features of my design for the wringer mop disclosed reside in the detachable presser plate having the perforated and ribbed pattern shown.

I claim:

The ornamental design for a wringer mop, as shown and described.
